HARRY A. KOENIG, OF PHILADELPHIA, PENNSYLVANIA.

EDGE TURNING AND PRESSING MACHINE.

1,275,044.

Specification of Letters Patent.

Patented Aug. 6, 1918.

Application filed January 8, 1918. Serial No. 210,859.

To all whom it may concern:

Be it known that I, HARRY A. KOENIG, a citizen of the United States, residing at Philadelphia, county of Philadelphia, and 5 State of Pennsylvania, have invented a certain new and useful Edge Turning and Pressing Machine, of which the following is a specification.

The present invention relates to an edge-10 turning and pressing machine and has for an object to provide means for accurately turning the margin of a piece of fabric and forming a crease about the periphery of the fabric whereby the turned margin remains 15 in place without basting and the fabric article can be sewed to the garment through the folded margin. In devices of this character as heretofore employed, the expedient of heating the table upon which the fabric 20 is placed has been tried in order to form a more perfect crease to prevent the folded margin from opening up after it has once been operated upon. Such heating devices have proven unsatisfactory however, because 25 the face of the fabric must rest upon the table and as the latter becomes very hot in use, the fabric is scorched and burned so that the losses from this defect have been considerable. In my present invention, all 30 the advantages of a heated pressing means are obtained without the disadvantage of having fabrics spoiled by being scorched upon the hot table, since the table of my invention remains cool at all times and the 35 applied heat acts upon the back or wrong side of the fabric and thus eliminates damage.

For the purpose of illustrating my invention, I have shown in the accompanying 40 drawings one form thereof which is at present preferred by me, since the same has been found in practice to give satisfactory and reliable results, although it is to be understood that the various instrumentalities of which my invention consists can be 45 variously arranged and organized and that my invention is not limited to the precise arrangement and organization of the instrumentalities as herein shown and described.

50 Referring to the drawings:

Figure 1 represents a side elevation of an edge turning machine embodying my invention.

Fig. 2 represents a plan of the same.

55 Fig. 3 represents a bottom plan detail of the burner construction.

Fig. 4 represents the shield construction for the burners.

Fig. 5 represents a bottom plan of the machine table.

Fig. 6 represents a section on line 6—6 of Fig. 2.

1 designates the frame of the machine which forms a substantial support for the table 2 upon which the work or articles to be turned and pressed are placed for proper manipulation by the machine elements. In order to hold the work in position upon the table 2, a lever arm 3 is pivoted to the table as indicated at 4 and carries on its inner end a rod 5 which in lowered position of the arm 3 is substantially over the center of the table. This rod 5 is adjustably connected to the arm 3 by a set stud 6 and terminates at one end in a laterally turned part forming a handle 7 by which the arm and its adjuncts are moved as desired. The other end of the rod 5 is adapted to receive a collar or bushing 8 which is removably held by a set stud 9, while the bushing is fixed to and forms a part of a plate die 10, the one here shown being in the shape of a pocket. It will be understood that there are a number of such dies each of a shape corresponding to the contour of the article, the edges of which are to be turned and the rod 5 may thus be equipped with any selected die according to requirements. The arm 3 is provided with a counterweight 11 for suitable balancing of the parts as will be understood. A buffer 46 forms a part of the counterweight 11 to prevent jar should the arm 3 be raised so that the end comes into contact with the table. The plate die is preferably of relatively thin material and its outer periphery edge follows the contour of the article but is spaced from the edge of the article all the way around in order that the portion of the article or goods which projects beyond the die may be folded or turned back in the manner desired. This turning or folding of the edge of the article is accomplished in the present instance by a plurality of dies 12 which are movable toward and away from the edge of the plate die 10. In some instances, but one of the dies 12 is necessary for the desired purpose so that the invention is not to be restricted to a plurality as shown.

In view of the fact that the dies 12 and the adjuncts thereof are all of similar construction and operated in a like manner, the

present description will deal with but one and like parts of the other dies will be provided with corresponding reference numerals. As here shown, the die 12 is substantially of Y-form having a flat bottom surface adapted to slide readily upon the table and having an edge 13 shaped to conform to the contour of the edge of the article or material it is adapted to engage. This edge 13 is 5 juxtaposed to the edge of the die 10 and is suitably beveled, as indicated at 14, so that the material edge rides upon this surface 14 and can then be turned back over the die 10 as the die 12 continues its movement.

10 15 designates a slide guided by ribs 16 of the table 2 and detachably connected to the die 12 by stud bolts 17 so that different dies 12 may be substituted as desired. A bridge piece 18 is bolted from one rib 16 to the other to form a top bearing for the slide 15 and prevent its displacement. The slide 15 is reciprocated at will by a suitable mechanism concealed beneath the table 2 and consisting in the present instance of a pivoted star 15 wheel 19 having radial arms 20 and a lug 21 to which latter there is connected a link 22. This link 22 joins a reciprocable bar 23 mounted upon the lower surface of the table 2 and actuated by a link 24 and bell crank 25 connection 25 with a rod 26 which is connected to the pivoted treadle lever 27. This construction provides for turning the star wheel 19 in one direction and a spring 28 bearing against the bar 23 returns the parts 30 to normal position when the treadle is released. 29 designates guide lugs on the table to form bearings for the bar and maintain it in proper alignment. The stroke of the bar 23 may be varied or adjusted as desired by a feed screw 30 threaded through a fixed part 31 and bearing against a suitable abutment 32 or the like on the bar 23.

Turning now to the transmission of motion from the star wheel 19 to the respective slides 15, it will be seen by reference to Fig. 5, that links 33 are connected respectively by pins 34 to the respective slides 15 and consequently as the star wheel turns the several slides 15 are simultaneously moved 45 either toward the center of the table or away according to the direction of movement of the said wheel 19. The table 2 is provided with slots 35 to receive the respective pins 34 and permit relative movement between the slide and table as will be 50 apparent.

In the present construction, each of the turning dies is provided with a heating means and as these are similar in construction, the description will be limited to one and like reference numerals applied to all.

Referring to Fig. 3, 36 designates, generally, a burner casing preferably of a shape following the configuration of the die 65 and therefore as here shown comprising two

diverging heat chambers 37 with an open bottom so that the flame from the two-way burner 38 impinges directly upon the upper surface of the die. The burner is suitably secured to the die by bolts 39 or equivalent 70 fastening means and as its upper bounding walls are curved and closed to the exterior, the heat is deflected and concentrated where desired upon the dies. Air to support the combustion is admitted by way of rear openings 40 as will be apparent. 41 designates an inlet supply pipe for gas which is connected to any suitable source though it should be noted that the gas is under regulated pressure to give the desired heating effect. 42 designates shields suitably shaped to cover the respective burners and thus present relatively cool exterior surfaces and at the same time the heat is retained in the walls of the burners. These shields are secured by studs 43 passing through the apertured ears 44 as will be understood though any well known means may be employed for this purpose. The operation of the machine is as follows: A shaped piece of material 45 is located upon the table 2 beneath the overhead die 10 which is then brought down by hand into contact relation with the material. The die 10 as previously explained is of smaller dimensions than the 95 material so that the latter has a continuous exposed margin projecting beyond the peripheral edge of the die. Now that the material is properly located and clamped, by holding the die 10 in contact with it, the foot 100 treadle 27 is pressed down and the several dies 12 advance simultaneously toward the stationary die 10 and finally, not only inclose the die 10 on all its side edges but at the same time, pick up the exposed material 105 and turn it back over the top surface of the die 10. It will be understood that the burners for the dies have been lighted and the dies 12 heated to the desired degree before they are brought into engagement with the 110 material. In consequence of this, the turned material is turned, heated and pressed at one operation throughout its peripheral length and when the dies 12 are backed off, by releasing the treadle 27 and the die 10 lifted, 115 the material may be removed in finished condition in so far as the edge turning is concerned. By this construction, it has been found that the edge is turned and pressed so accurately as to the line of the fold that 120 basting of the turned part is unnecessary and the article may be sewn directly to the part of which it forms a portion.

It will now be apparent that I have devised a complete unitary machine adapted 125 for the purpose intended wherein a fabric of predetermined shape may have its margin turned in the required manner and so pressed as to be retained in folded condition without subsequent basting and wherein the turning 130

and pressing operations are carried out simultaneously and without danger of scorching the body of the fabric.

It should be noted also that the burner shields are so located that any excess material of the fabric being folded cannot come into direct contact with the top of the burners and thus become damaged. While the burners are in the present instance shown as gas operated it should be understood that the invention is not to be construed as limited to this particular heating means as obviously any well known means for directing heat upon the dies may be employed.

What I claim is:

1. In a machine of the character stated, a table, a die adapted to hold a piece of fabric upon said table, a plurality of movable dies mounted for sliding movement on said table and adapted to fold the edge of said fabric over said holding die, gas burners respectively mounted upon said movable dies to maintain said movable dies in heated condition, means to shift all of said movable dies at will and means to concentrate the burner heat upon the respective dies.

2. In a machine of the character stated, a table, a die of relatively thin material adapted to hold a piece of fabric upon said table, said die having a configuration conforming to the contour of said fabric and being of a size to leave a marginal edge of material projecting beyond said die, a plurality of movable dies slidably mounted upon said table and each having an edge conforming to the shape of a portion of said fabric, gas burners for heating the respective dies and means for simultaneously moving said dies and burners toward said holding die whereby the fabric edge is turned over said holding die and pressed.

3. In a machine of the character stated, a table, a die of relatively thin material adapted to hold a fabric upon said table, said die having a configuration conforming to the contour of said fabric and being of a size to leave a marginal edge of material projecting beyond said die, means movable at will to locate said holder with respect to said table, a plurality of movable dies slidably mounted upon said table, each having a beveled edge conforming to the shape of a portion of said fabric, gas burners for heating

the respective dies and means for moving said dies and burners toward said holding die whereby the fabric edge is turned over said holding die and pressed.

4. In a machine of the character stated, a table, a die of relatively thin material adapted to hold a fabric upon said table, said die having a configuration conforming to the contour of said fabric and being of a size to leave a marginal edge of material projecting beyond said die, means movable at will to locate said holder with respect to said table, a plurality of movable dies slidably mounted upon said table, each having a beveled edge conforming to the shape of a portion of said fabric, gas burners for heating the respective dies, means for moving said dies and burners toward said holding die whereby the fabric edge is turned over said holding die and pressed and means to prevent the material from contacting with the top surface of said dies.

5. In a machine of the character stated, a table, a die arranged to hold a piece of fabric upon said table, a plurality of dies mounted for sliding movement on said table to engage and fold the edge of said fabric over said holding die, gas burners respectively mounted on said movable dies to maintain said movable dies in heated condition, means to shift all of said movable dies at will and a plurality of shields respectively secured to said movable dies for deflecting the flame of said gas burners respectively upon the top of said movable dies.

6. In a machine of the character stated, a table, a die arranged to hold a piece of fabric upon said table, a plurality of dies mounted for sliding movement on said table to engage and fold the edge of said fabric over said holding die, gas burners respectively mounted on said movable dies to maintain said movable dies in heated condition, means to shift all of said movable dies at will, a plurality of shields respectively secured to said movable dies for deflecting the flame of said gas burners respectively upon the top of said movable dies, and means respectively inclosing said burners to prevent said fabric coming in contact with said burners.

In testimony whereof, I have hereunto signed my name.

HARRY A. KOENIG.
